United States Patent Office

Des. 224,647
Patented Aug. 22, 1972

244,647

BUILDING BLOCK

Stanton L. Friedman, 11535 Renwick,
Houston, Tex. 77035

Filed Mar. 19, 1970, Ser. No. 21,977

Term of patent 14 years

Int. Cl. D25—03

U.S. Cl. D13—1

Fig. 1.

Fig. 2.

Fig. 3.

Fig. 4.

FIG. 1 is a top, front and left side perspective view of a building block embodying my new design, the doors within A-frame entrance being shown of rectangular contour;

FIG. 2 is a top, rear and left side perspective view thereof;

FIG. 3 is a top, front and left side, fragmentary, perspective view, showing another modification of entrance in which the doors within the triangularly shaped space within A-frame entrance are shown of special quadrilaterally shaped contour; and

FIG. 4 is a top, front and left side smaller scale perspective view, in general correspondence with the view shown in FIG. 1, in which the doors within the triangularly shaped space within A-frame entrance are shown of special, upwardly rounded contour.

I claim:

The ornamental design for a building block, as shown and described.
